UNITED STATES PATENT OFFICE.

OLIVER J. MICHAELS, OF PITTSBURG, PENNSYLVANIA, ASSIGNOR OF ONE-THIRD TO CHARLES WRIGHT PROVOST, OF SAME PLACE.

CAR-COUPING.

SPECIFICATION forming part of Letters Patent No. 326,882, dated September 22, 1885.
Application filed July 13, 1885. (No model.)

To all whom it may concern:

Be it known that I, OLIVER J. MICHAELS, of Pittsburg, in the county of Allegheny and State of Pennsylvania, have invented certain new and useful Improvements in Car-Couplings; and I do hereby declare that the following is a full, clear, and exact description of the invention, which will enable others skilled in the art to which it appertains to make and use the same, reference being had to the accompanying drawings, which form a part of this specification.

This invention relates to an improved form of car-coupling; and it consists in the peculiar construction and combination of the draw-head and coupling-pin, substantially as hereinafter fully described and claimed.

In the accompanying drawings, Figure 1 is a longitudinal vertical section of the draw-head, and Fig. 2 is a perspective view of my improved form of coupling-pin. Figs. 3, 4, and 5 are longitudinal sections of paired draw-heads in different relations, Fig. 3 showing the coupled position while in use, Fig. 4 showing the coupling-pin on the right as set for self-coupling with the link striking it, and Fig. 5 shows the same pin drawn back about to be tilted by drawing upwardly the chain. Fig. 6 is a view of one end of a car provided with my draw-head and coupling devices.

More particularly my invention is as follows:

The coupling-pin A is an L-shaped device forming, substantially, a right-angle, and at the angle projects laterally on each side the pivots or trunnions b, the angle back of these (marked c) being rounded off to substantially describe a circular face on the axis of said pivots.

The draw-head D is of the usual massive form in front, with its faces converging to the link-opening e, from which a horizontal slot or groove, f, extends backwardly into the draw-head, forming a cavity of sufficient length and width to accommodate the link g in all its movements for coupling and uncoupling and during the oscillation of the car in motion. A vertical slot, h, is formed lengthwise of the draw-head along its center, and of a width just enough greater than the thickness of the pin A to allow the latter to move freely. Slot h has greater vertical depth than the link-slot or groove f, and is also longer, but only

begins at the rear of the enlarged front of draw-head D, where it is formed square to make the abutments i i which receive the strain of the pin A when in use. In the lower part of the walls of slot h, I form the horizontal pivot-slots k, opening near the front upwardly into the link-slot f, as shown in Fig. 1. The link A is slipped in through the front and its pivots b lowered till they rest in the pivot-slots k, wherein they can slide freely forwardly or backwardly. I prefer to make the rear member of the pin A somewhat heavier than the other portion. By reason of the position of the pivots b, the link A always gravitates toward the front or rear, as shown in the figures. I attach a chain, m, to its rear end, which is carried thence up to or near the roof of the car, and by a branch over a pulley, N, laterally along the front of the platform or car-timbers to a suitable lever, P.

Referring to Fig. 4, the facility for automatic coupling will be readily understood. In the draw-head, at the right of the figure, the pin A is drawn back and turned over so as to have its front member horizontal, which is the only preparation required. The link g of the other draw-head, when the cars come together, strikes the now uppermost rear portion of pin A, which, immediately turning on its pivots, so tilts over backwardly, and its front part enters the link and assumes a vertical position. The opposite movement of the link then, since the pivots b are free to move in that direction, simply carries the pin A bodily forward till it strikes the abutments or shoulders i i, and the coupling is effected.

To uncouple, the cars are moved together slightly, after which the chain m is used to withdraw the pin A backwardly till it takes the position shown by Fig. 5, when a further pull on the chain tilts the pin into the position shown by Fig. 4, whereupon the link is free and the car uncoupled.

The cars can thus be coupled and uncoupled with perfect ease without any necessity for the brakeman to risk his life between the cars, all the required manipulations being accomplished with great facility by the use of the chain only.

To accommodate a common coupling-pin, I form the cavity s in the under wall of the draw-

head, which forms a socket to sustain the pin in the ordinary position.

I claim as my invention—

1. In a car-coupling, the draw-head D, having link-opening *e* and groove *f*, vertical pin-slot *h*, and abutments *i i*, in combination with the right-angle pin A, located in said slot *h* and adapted to stand with either its front or rear portion vertical, and having lateral pivots *b* at its angle, substantially as described.

2. In a car-coupling, the draw-head D, having link-opening *e*, groove *f*, vertical pin-slot *h*, abutments *i i*, and horizontal pivot-slots *k*, in combination with the right-angled pin A, having lateral pivots *b*, substantially as described.

3. In a car-coupling, the combination of the draw-head D, having link-opening *e*, groove *f*, pin-slot *h*, and abutments *i i*, with the right-angled pin A, having pivots *b*, and a chain, ^{2c} *m*, extending to the top, side, or other desired part of the car, substantially as described.

In testimony that I claim the foregoing as my own I have hereto affixed my signature in presence of two witnesses.

OLIVER J. MICHAELS.
